UNITED STATES PATENT OFFICE.

RICHARD FALTER, OF BROOKLYN, NEW YORK.

BABY PANTS.

1,402,588.

Specification of Letters Patent   Patented Jan. 3, 1922.

Application filed April 3, 1920. Serial No. 371,035.

To all whom it may concern:

Be it known that I, RICHARD FALTER, a citizen of the United States, and a resident of the city of New York, borough of Brooklyn, in the county of Kings and State of New York, have invented new and Improved Baby Pants, of which the following is a full, clear, and exact description.

The object of the invention is to provide a new and improved baby pants or diaper cover arranged to permit convenient adjustment at the waist, sides and legs to properly fit the garment to the baby's body and to compensate for the increase in size in the baby's body due to the growth thereof.

Another object is to dispense with hooks, buttons or similar protruding and undesirable adjusting and fastening devices.

With these and other objects in view, the invention consists of certain novel features of construction as hereinafter shown and described and then specifically pointed out in the claim.

A practical embodiment of the invention is represented in the accompanying drawings forming a part of this specification, in which similar characters of reference indicate corresponding parts in all the views.

Figure 1 is a perspective view of the baby's pants or diaper cover as applied;

Figure 2 is an elevation of one of the adjustable sides of the pants with the parts adjusted to the fullest extent;

Figure 3 is a similar view of the same with the parts adjusted to intermediate position;

Figure 4 is a similar view of the same with the parts adjusted to smallest position; and

Figure 5 is a reduced plan view of the body of the garment spread out.

The body 10 of the baby pants or diaper cover is made from a single piece of suitable fabric material having approximately parallel ends, curved cut-out portions at the sides of the median line, and converging side edges extending from the cut-out portions to the ends, and the said single piece when doubled up along the broken line shown in Figure 5 provides a body open at the sides and forming legs 11 for the passage of the legs of the baby, as will be readily understood by reference to Figure 1. The upper end of the body 10 is provided with front and rear sections 12 and 13 of a waistband, and the edges of the body at each side are provided with bindings 14 and 15 con-

nected at their upper ends with the waistband sections 12 and 13 and connecting at their lower ends with bindings 16 and 17 at the lower ends of the legs 11.

In order to close the open sides of the body 10 and to provide adjustment for the sections 12 and 13 of the waistband and the bindings 16 and 17 of the legs 11, use is made of a single lacing string 20, one for each side, and laced through eyelets 21, 22 formed in the side bindings 14 and 15 and passing through selected sets of eyelets 23, 24 at the waistband sections 12 and 13, and similar eyelets 25, 26 arranged in the leg bindings 16 and 17. The lacing string is engaged at its middle with a corresponding pair of eyelets 25, 26, and is then laced through the eyelets 21, 22 and finally passed through a selected pair of eyelets 23, 24, after which the ends of the lacing string 20 are tied into a bow knot 30 at the upper end of the corresponding side of the garment, as will be readily understood by reference to the drawings.

When the baby pants or diaper cover is first used on the baby's body, the lacing string 20 is engaged with the lowermost pair of eyelets 25, 26 and with the outermost pair of eyelets 23, 24, as plainly indicated in Figure 4. As the baby grows, the lacing string 20 is engaged at its lower end with the next following pair of eyelets 25, 26 at the legs and with the next following pair of eyelets 23, 24 at the waist, as plainly shown in Figure 3, thus enlarging the legs and waistband of the body 10 to suit the growth of the baby. Later on, the lacing string 20 is engaged with the uppermost pair of eyelets 25, 26 and the innermost pair of eyelets 23, 24, as shown in Figure 2, to further compensate for the increase in the baby's body at the legs and waist. It will also be noticed that the body 10 may be enlarged by correspondingly loosening the lacing string 20 at the eyelets 21, 22. Draw strings 40 are preferably arranged at the rear of the body 10 as an additional means of adjustment at the waistband.

From the foregoing it will be seen that by the arrangement described the baby pants or diaper cover can be conveniently adjusted at the sides, waist and legs to properly fit the garment on the baby's body and to compensate for the increase in size of the baby's body due to the growth thereof. It will also be noticed that by the use of eyelets and the

draw string undesirable protruding or projecting fastening devices are dispensed with.

Having thus described my invention, I claim as new and desire to secure by Letters Patent:—

Baby pants, comprising a body made of a single piece of material having curved cut-out leg portions at the sides of the median line and converging side edges extending 10 from the cut-out portions to the upper front and rear waist band sections of the body, the side edges at each side having oppositely arranged eyelets, and the ends of the waist-

band sections and the leg portions having a plurality of eyelets, and lacing strings, one 15 for each side of the body, each of said lacing strings engaging the oppositely arranged eyelets of the side edges and engaging a selected pair of eyelets of the ends of the corresponding leg portions and a selected pair 20 of the eyelets of the corresponding adjacent waistband ends to allow of progressively enlarging the baby pants to compensate for the increase in the size of the baby's body.

RICHARD FALTER.
